UNITED STATES PATENT OFFICE.

HUGO DORNSEIF, OF RADEVORMWALD, GERMANY.

APPARATUS FOR HARDENING THE RUNNERS OF ICE SKATES.

Application filed March 24, 1927, Serial No. 177,984, and in Germany March 30, 1926.

In regard to skate-blades the demands which have to be met are, firstly, that the edges (which are usually widened) must be as hard as possible (glass-hard) while, secondly, the remaining parts of the blade must be considerably less hard than the edges in order that they may be able to resist breakage. For this reason skate blades have hitherto been made of rolled iron and a thin, hard layer of steel has been welded on to the widened edge of the blade. Apart from manufacturing difficulties in correctly fixing this layer of steel and the unreliability arising therefrom, there is also the great disadvantage that the kinds of steel suitable for the welding do not acquire the high degree of hardness desired and also can not acquire it because, owing to the very different temperature co-efficients of expansion of steel and iron, considerable changes in shape take place on hardening the steel, which necessitate a subsequent adjustment of the skate of which the edge has been hardened. The skates therefore have indeed the desired resistance to breaking but do not possess the necessary hardness of edge, so that the desired high resistance to wear at the edge is lacking. It must also be added that skates having a welded steel edge are very expensive, not only on account of the difficulty of manufacture but also because only the best Swedish steel can be used for welding.

All these drawbacks are avoided in the new skate with hardened edge. According to the invention the entire blade of the skate consists of one piece of good material (tool steel), capable of being hardened. It is, however, made glass-hard exclusively at the edge, i. e., the parts which run on the ice. The remaining parts of the blade on the other hand have the natural hardness of the material.

The manufacture of the new skate can be effected by heating the edge by jets of flame, the remaining parts of the blade away from the edge being protected, and then suddenly cooling it by means of a cooling and hardening liquid, for example water. When carrying out this process the edge can be heated simultaneously along its entire length and cooling can be effected by immersion in a hardening bath. A better way, however, is to heat the edge by means of a jet of flame of limited extent proceeding continuously from one end to the other but only heating

say, by heating the edge, as it were, in sections and then cooling the heated portion of the edge directly after it has been heated by means of a stream of water. In this way the advantage is obtained in the first place that fresh cooling liquid of uniform temperature can always be employed with the result that a uniform degree of hardness is obtained with all skates. Further, owing to the fact that not only the intensity of the jet of flame but also the speed with which the blade of the skate is moved across the jet can be regulated, it is possible to regulate the depth to which the hardening effects penetrate, in such a manner that the edge is made glass-hard to a depth which is sufficient for the sharp edges to be maintained for a long time while the rest of the blade retains its original, soft condition. For chilling the heated portions of the edge two streams of water are preferably employed which act on the edge from opposite sides and at right angles to its longitudinal direction. By this means it is possible to regulate the cooling in such a manner that, on the one hand, distortion or bending of the skate-blade is prevented while, on the other hand, any bending which may have occurred in any of the preliminary stages of manufacture is again put right.

In order that, when the edge is heated, the heat conducted to it may not spread to the remaining parts of the blade of the skate the edge must be heated as quickly as possible. It is advantageous therefore to employ jets of flame of very high temperature for which purpose the burner is best supplied with a mixture of acetylene gas and oxygen.

Two constructional embodiments of apparatus for carrying out the new process are illustrated diagrammatically by way of example in the drawings, in which

Fig. 1 is a side elevation of the first example on a greatly reduced scale, omitting the burner supporting and actuating means.

Fig. 1^a is a plan view of the burner and related parts,

Fig. 1^b is a cross-section of the same,

Fig. 2 a cross-section through the work-piece holder of this device on a somewhat greater scale than in Fig. 1,

Fig. 3 a front elevation of the device in accordance with the second example on a reduced scale,

Fig. 4 a side elevation, and

Fig. 5 a view of a portion of the driving means belonging thereto.

Referring to Figs. 1 and 2 of the drawing, 5 the device consists essentially of a trough or receptacle *a* containing the cooling or hardening liquid and a revoluble wheel *b* about half of which is immersed in the trough *a*. The wheel *b* is preferably made of cast iron 10 and is provided at its circumference with a narrow peripheral slot *c* which serves the purpose of receiving the blade *d* of the skate, and is of such dimensions that the unwidened part of the blade just passes into the slot 15 while the widened edge of the blade projects outwardly beyond the circumference of the wheel. The skate-blades are inserted at regular intervals in the slot *c* and are fixed in it, for which purpose a side clamping 20 screw *f* is provided for fixing each blade.

At one side of the trough and just above its edge there is provided a long, narrow burner *g* which extends over the entire length of the edge of the blade and preferably somewhat beyond it. This burner has a large number of openings directed towards the wheel *b* at which small jets of flame burn. The burner is advantageously moved backwards and forwards in the longitudinal direction of the skate-blade through a distance which is equal to the distance apart of the individual openings or the width of the cone of flame, that is to say, in the example illustrated in Fig. 1, between 25 the limits bounded by the dotted lines I, II, so that all parts of the blade are uniformly swept by the individual cones of flame. In this way the thickened edge of the blade is heated uniformly and so quickly 30 that the heat cannot be transferred to the other parts of the blade which lie protected in the slot in the wheel. The burner *g* may be constructed and operatively mounted so as to be reciprocated by hand or by power mechanism. When operated by power mechanism the burner, as shown in Figures 35 1^a and 1^b, may be mounted in a suitably supported guideway *g'* and coupled by a connecting rod *g²* to a crank shaft *g³* driven by 40 chain and sprocket gearing *g⁴*, or other suitable gearing, from a suitable power source. The power driving arrangement may be such that the burner will be reciprocated either 45 continuously or only at such a time as when 50 a skate is in position to be heated thereby. When the edge has been heated to the desired degree the wheel is quickly turned in the direction of the arrow through such an angle that the heated edge is brought into 55 the hardening bath and the following skate-blade is brought in front of the burner in place of the former blade. The skate blade which is dipped into the liquid assumes the 60 high degree of hardness desired at the 65 strongly heated edge owing to the chilling

while the other remaining parts of the blade are not affected by it. Simultaneously with the immersion of the heated blade on the one side of the wheel a cool blade is lifted up out of the liquid on the other side of the wheel 70 when the wheel is turned and can be exchanged for a fresh unhardened blade which on turning the wheel further is brought to the heating place.

The movement of the wheel while it is 75 being turned preferably takes place rather quickly so that no substantial cooling of the heated blade can occur on its way into the liquid and, on the other hand, the fresh blade is quickly brought in front of the 80 flame, so that heat losses do not occur in the interval and an economical consumption of fuel results.

The means for turning the wheel can be of any desired known form, and as shown in 85 Figure 1, may consist of a sprocket gear *b'* fixed on the axle of the wheel and driven by a chain *b²* from any suitable power source in such manner that the wheel may be moved each time the required distance to bring a 90 skate in position to be acted upon by the burner *g* and held in such position during the heating action. The turning mechanism is best arranged in such a manner that the turning takes place automatically at fixed intervals of time when the skate blade which is in front of the burner has reached the necessary 95 temperature.

In the example illustrated the diameter 100 of the wheel *b* is so great that its circumferential curvature is about equal to the curvature of the blade of the skate. If desired, however, the diameter of the wheel may be different and, at the places where the blades are fastened separate pieces which correspond in shape to the shape of the blade can be inserted. In this case the slot *c* need not extend around the whole circumference of the wheel, instead a large number of separate grooves or slots each of which is suitable 105 for the reception of a skate blade may be provided.

Further the slots for the reception of the blade instead of being arranged in the circumferential direction of the wheel could 115 also be arranged at right angles thereto, that is to say, besides one another parallel to the axis of the wheel. In this case the diameter of the wheel would be considerably reduced.

In the example illustrated in Figs. 3-5, 1 120 and 2 are two fixed cheeks which are arranged at a distance apart which is equal to the thickness of a skate-blade, and the resulting slot *3* serves the purpose of receiving the unwidened part of the skate-blade *4* to be treated. The front of the cheeks 1 and 2 is curved to correspond with the curvature of the edge *5* of the skate-blade, so that when the blades *4* are inserted from above into the slot *3* the strengthened edge *5* projects for 125 130

wardly out of the slot 3 and only this portion of the blade is heated by a jet of flame, as hereinafter described. The cheeks 1 and 2 serve the purpose of a lateral protection for 5 the unwidened parts of the blade during the heating process, so that these parts therefore cannot be touched by the flame.

The blades 4 are moved along the slot 3 by suitable feeding means until they reach 10 the lower end of the slot. For this purpose there are provided inside the cheeks 1 and 2, and at both sides of the slot several pairs (in the example illustrated three pairs) of opposing rollers 7, 8, 9 by which the workpiece 15 4 is drawn along in the slot 3. During this movement the work-pieces are prevented in a very simple manner from being pressed forwardly out of the slot by means of a number of convex rollers 11, 12, 13 arranged at 20 the side of the slot 3 against which the edge 5 bears.

The rollers 7, 8 and 9 are fastened respectively to the front end of shafts 14, 15, 16 which are journalled in the body of the 25 cheeks 1, 2 and carry at their other ends spur wheels 17, 18, 19 respectively which are themselves driven through the agency of two coupling wheels 20, 21 by means of a worm-wheel 22. The spur wheels 17, 18, 19, 30 fixed on the shafts 14, 15, 16, are all of the same diameter so that the work-piece 4 which is held between several pairs of rollers can be fed forward quite uniformly.

The worm wheel 22 co-acts with the worm 35 23 the shaft 24 of which carries a disc 25 at one end. On the flat surface 26 of this disc 25, which is constructed as a friction disc, there runs a driving friction roller 27, which, for the purpose of regulating the 40 speed of the drive, is movably held on the main shaft 28 which is driven by means of a belt 30. The roller 27 can be moved backwards and forwards radially over the disc 26 by means of a rod 31 which is provided 45 at its free end with a handle 32 and of which the other end 29 is forked to engage the roller 27, so that any adjustment of the speed at which the work-piece is fed forwards as may be desirable or necessary, can 50 be made in small steps. The main shaft 28 is carried in two bearings 33, 34, which are provided in an arm 35 of an upright 37 which is fastened by screws 36 to the side of one of the cheeks 2.

55 A burner 38, which serves the purpose of heating the widened edge 5 of the skate-blade 4 which projects out of the slot 3, is arranged at about the middle of the two cheeks 1, 2. The free end of the burner 38 60 is provided with two branch tubes 39, 40 for connection to the air and gas supply, the admission of which can be regulated by cocks 41, 42 respectively. The front portion 65 of the burner 38 is bent downwards so that the actual body 43 of the burner can be

cooled in manner known by means of liquid supplied through the tube 44. Below the body 43 of the burner there is arranged a device for supplying cooling liquid, the purpose of which is to chill the heated parts of 70 the edge 5 immediately after the heating process is concluded. To this end there are provided two water pipes 50, 51, having regulating cocks 47, 48 respectively, the front ends of which pipes are connected together by means of a cross pipe 52, which is held in position by means of a downwardly projecting nose 53 of the burner body 43. The cross pipe 52 is provided opposite the slot 3 with a slot into which the 80 heated edge enters, so that when the device is in operation the water from the two tubes 50, 51 can act from opposite sides on the heated blade and cool it instantaneously.

In order that the body of the cheeks may not be affected by the powerful jet of flame 85 chambers 55 and 56 for the reception of cooling water are provided at the sides of the slot 3 which is conducted to and from them through the pipes 57, 58.

90 For protecting the burner and the tube 44 which is inserted in the burner body 43, an insulating plate 6 which holds back the flame is arranged above the body 43, this plate also prevents the flame from striking upwards and heating any parts of the blade edge which are above the burner.

The method of operation of the device is as follows:

The work-pieces, i. e. the blades 4 are advantageously introduced into the slot 3 with their points in front in such a manner that their widened edge projects out in front of the working side of the cheeks 1 and 2. The convex rollers 11, 12, 13 arranged over the 100 slot 3 prevent the blade 4 from falling forwardly out of the slot 3. The work-piece is drawn downwards and brought in front of the burner body 43 by the upper pair of rollers 7, the periphery of which is preferably covered with a layer of rubber 60 in order to grip the work-piece 4 more securely. When in front of the burner, the edge 5 which projects out of the slot 3 is continuously heated from one end to the other by 105 the flame as the blade moves steadily forwards, while the other parts of the blade 4 are protected by the cheeks 1 and 2 so that they cannot be touched by the flame. The steady forward feed of the work-piece 4 can 110 be altered so as to proceed at different speeds by adjusting the driving roller 27 which acts with the disc 25.

115 Directly after the heating process during which always a portion only of the length of the blade-edge is operated on, the heated parts are cooled by the streams of water from the cross pipe 52 which impinge on the blade-edge. As hereinbefore mentioned, the 120 cooling can be regulated in such a manner 130

that, on the one hand, distortion of the blade is prevented and, on the other hand, any deformation which may have occurred during previous treatment is again remedied. 5 This is due to the fact that the edge of the blade as it passes the flame is heated in sections and is then immediately cooled. Finally the work-piece falls out of the slot 3 into a container 61 filled with liquid from 10 which the finished work-pieces having glass-hard edges are removed.

Owing to the possibility of being able to effect various adjustments the apparatus operates with exactness and great reliability. 15 Further, owing to the fact that the work-pieces can be introduced into the slot 3 so that they follow on directly one after another (even when one or more work-pieces are in the slot 3) it is possible to carry out 20 the process extraordinarily quickly.

The second example also may be modified in many points, for example the work-pieces can be clamped in the work-piece-holder and, instead of the work-pieces being movable, 25 the burner and the spraying device can be arranged to be movable in such a manner that they can be guided from one end to the other of the edge of the skate-blade to be hardened. Further, the feeding rollers 30 instead of being driven by friction gearing could also be driven by other suitable form of gearing. Further, the work-piece holder according to Figs. 1 and 2 consisting of a 35 rotating drum or wheel can also be employed with advantage in the example according to Figs. 3-5. The drum or wheel is not then moved intermittently in the manner described with reference to Figs. 1 and 2 but is rotated continuously. 40 For the purposes of the invention it is of no importance whether the edge of the blade, is widened out as has been assumed in the examples described, or whether it is of the same width as the remaining portions of the 45 blade.

In the hereinbefore described methods of carrying the new process into operation, when the edge is heated approximately the same amount of heat is conducted to all 50 parts of the edge. It could therefore happen particularly when the ends of the blade are tapered or reduced, that the ends of the blade-edge, owing to the fact that it is possible to conduct away the heat to the rest of 55 the edge on one side only, would become overheated and would consequently either be burnt or lose their shape owing to becoming soft. This danger can be prevented, in accordance with the invention, by conducting a 60 smaller amount of heat to the ends of the edge when the edge is heated than to the remaining parts of the edge of the blade. This can be done either by shortening the duration of the action of the flame on the 65 ends of the edge or by reducing the intensity

of the flame acting on the ends of the edge.

For example, in the form of construction described with reference to Figs. 1 and 2 in which the edge of the blade of the skate is heated simultaneously over its entire length, 70 a burner can be employed of which the length is somewhat less than the length of the edge and which is moved backwards and forwards in the longitudinal direction of the blade of the skate between two limits defined by the ends of the edge of the blade. The result of this arrangement is that, during the backward and forward movement of the burner the flames are alternately removed from the one or other end of the edge 80 so that these ends are exposed to the action of the flame to a somewhat less extent than the rest of the edge. Or, when employing a burner in accordance with Fig. 1 extending over the entire length of the edge, the burner 85 can be so arranged that smaller jets of flame are formed at its end than at the rest of the burner which also produces less heating of the ends of the edge.

If, however, the blade is heated, as described with reference to Figs. 3-5, in such a manner that the blade of the skate is passed with its edge under a burner which extends only over a portion of the length of the skate-blade, then the procedure can be 95 such that each time an end of the edge of the blade comes under the burner the speed of the skate-blade is temporarily increased and so the duration of the action of the flame on the ends of the edge is shortened. A similar result can be attained by weakening the intensity of the flame every time the ends of the blade come under the burner, the consequence of which also is that a smaller 100 quantity of heat is conducted to the ends of the edge than to the remaining parts of the edge. 105

In either case over-heating of the ends of the edge of the blade is prevented and therefore burning or softening at the ends 110 of the blade is avoided.

Obviously the above described examples could be reversed in such a way that when the entire length of the edge is heated simultaneously the blade is moved backwards and forwards instead of the burner and when a burner which extends only over a part of the length of the edge is employed the burner is moved in the longitudinal direction of the edge instead of the blade. 115

I claim:—

1. An apparatus for hardening the runners of skates, comprising a holder formed to cover the parts of the skate-blade except the runner edge, leaving only said edge exposed, 125 means for moving said holder for feeding the blade forward to treatment positions, a burner arranged in the path of feed movement of the skate-blade and provided with openings for projecting small jets of flame 130

- against the exposed edge of the blade, means for moving said burner backwards and forwards in the longitudinal direction of the skate, and a receptacle for hardening liquid arranged in the path of feed movement of the skate beyond the burner. 40
2. An apparatus for hardening the runners of ice skates, comprising means for enclosing and shielding the body of the skate so as to leave only the runner edge of the skate exposed, a heater for heating the exposed edge of the skate, means for producing relative motion between the skate so enclosed and shielded and the heater so as to shift the skate into and out of the heating zone of the heater, and means for cooling the heated runner edge when heated to a predetermined temperature. 45
3. An apparatus for hardening the runners of ice skates, comprising means for enclosing and shielding the body of the skate so as to leave only the runner edge of the skate exposed, a burner for projecting spaced jets of flame along the runner edge from end to end thereof, means for producing relative movement between the skate so enclosed and shielded and the burner so as to shift the skate into and out of the path of the burner, means for reciprocating the burner during its flame playing action on the runner edge, and means for cooling the edge of the skate when heated to a predetermined degree. 50
4. An apparatus for hardening the runner edges of ice skates, comprising a holder channeled to receive and shield the body of the skate, leaving only the runner edge of the skate exposed, a burner for projecting a series of spaced jets of flame against the edge of the burner from end to end thereof, means for moving the holder so as to shift the skate into and out of the path of the burner, means for reciprocating the burner while in action to cause the flames to be sprayed uniformly over the runner edge, and means for cooling the edge of the skate when heated to a predetermined degree. 55
5. An apparatus of the character described comprising a receptacle containing a cooling liquid, a rotary holder provided with peripheral channeled portions for receiving and shielding the body portions of skates arranged at predetermined intervals, leaving only the runner edges of the skates exposed, and a burner arranged in the path of rotation of the holder so as to permit the skates by rotation of the holder to be brought into position for the runner edges thereof to be heated by said burner, said burner being arranged adjacent to the receptacle, whereby each skate after having been heated to a predetermined degree may be quickly shifted by rotation of the holder out of heating position and immersed in the cooling liquid in the receptacle. 60
6. In an apparatus for hardening the runners of ice skates, a burner for heating the runner edge of a skate, means for enclosing and shielding the body portion of a skate to be exposed to the action of the burner so as to leave only the runner edge of the skate exposed for action thereon by the burner, means for cooling the edge of the skate, and means for feeding the skate to successive positions to be acted upon by the burner and the cooling means. 70

In testimony whereof I affix my signature.
HUGO DORNSEIF.
